UNITED STATES PATENT OFFICE.

EDWARD MEYER AND EMIL C. SCHIFFERS, OF SAN ANTONIO, TEXAS.

AXLE-LUBRICATOR.

No. 897,915.

Specification of Letters Patent.

Patented Sept. 8, 1908.

Application filed February 7, 1908. Serial No. 414,820.

To all whom it may concern:

Be it known that we, EDWARD MEYER and EMIL C. SCHIFFERS, citizens of the United States, residing at San Antonio, in the county 5 of Bexar and State of Texas, have invented certain new and useful Improvements in Axle-Lubricators, of which the following is a specification.

The present invention has for its primary 10 object to provide an improved axle lubricating device which is peculiarly designed so as to be readily applied to the hub of an ordinary wheel and which will operate in an effective manner to convey oil or lubricant to 15 the spindle and prevent the return thereof when the wheel is rotated.

The invention further contemplates a lubricating attachment of the character set forth which may be easily manipulated without 20 the use of a wrench or other tool, permits the oiling to be done instantly without removing the wheel, and can be readily cleaned in case of clogging through the use of impure oil.

For a full description of the invention and the merits thereof and also to acquire a 25 knowledge of the details of construction and the means of effecting the result, reference is to be had to the following description and accompanying drawings, in which:

Figure 1 is a longitudinal sectional view showing the invention applied to the hub of a wheel, portions being broken away. Fig. 2 is an enlarged sectional view through the lubricator cup. Fig. 3 is a transverse sectional view on the line 3—3 of Fig. 2. Fig. 4 is a top plan view of the cover. Fig. 5 is a view showing a split clamping ring for applying the lubricator to the wheel hub.

Corresponding and like parts are referred to in the following description and indicated in all the views of the drawings by the same reference characters.

Referring to the drawing the numeral 1 45 designates the hub of an ordinary wheel which is mounted upon the spindle 2 at one end of an axle 3, the said members being of the conventional construction and the upper portion of the spindle being shown as having 50 a longitudinal groove 4 therein for distributing the lubricant. The oil reservoir or cup 5 is mounted upon a base which is secured in any suitable manner to the hub 1, and this base may be in the nature of a rigid band 6; 55 or a split band 6^a, the ends of the said split band overlapping each other and having a

spring action which enables them to accommodate themselves to various sizes of hubs. In either instance however one end of the band is designed to project beyond the inner 60 end of the hub and to coöperate with the bolster to exclude sand from the spindle. The oil reservoir 5 projects beyond the edge of the band and communicates with an oil tube 7 extending from the exterior of the hub 65 to the spindle receiving opening therein and designed to lead the lubricant from the reservoir to the spindle. The reservoir 5 may be of any approved shape, although in the present instance it is shown as cylindrical, 70 and is provided upon its interior with a pair of annular grooves 8^a and 8^b. The cover 9 for closing the reservoir is formed with an annular flange 10 fitting closely within the reservoir and having a width corresponding 75 approximately to the depth of the reservoir. A pair of spring strips 11 are secured to the interior of the flange 10 at approximately diametrically opposite points, the free ends of the spring strips being received within recesses 12 formed in the body portion of the cover 9. Projecting from each of the spring strips 11 is a pair of locking lugs 13, the said lugs being designed to pass through openings in the flange so as to engage the grooves 8^a 85 and 8^b in the reservoir. Spindles 14 have a threaded connection with the free ends of the springs 11 and pass loosely through the cover 9 where they terminate in finger-pieces 15. It will thus be apparent that by pressing inwardly upon these finger-pieces the spring strips 11 will be forced away from the flange 10 and the locking lugs 13 retracted so as to 90 clear the walls of the reservoir when the cover is being placed in position or removed 95 therefrom.

When it is desired to lubricate the wheel, the finger-pieces 15 are pressed inwardly to retract the lugs 13 and the cover 9 removed from the oil reservoir 5. After the oil or lubricant has been placed within the reservoir, the cover is again applied thereto and the lubricant caused to flow through the tube 7 which delivers it to the spindle 2. When the cover is in position an air chamber is 100 formed above the lubricant and as the cover is forced inwardly the air is compressed and serves to force the lubricant through the feed tube. Should it only be desired to use a portion of the lubricant the lower set of lugs 13 105 are caused to engage the upper groove 8^a and the cover thereby locked in position with the 110

flange only partially received within the reservoir. On the contrary however should it be desired to force all of the grease or lubricant out of the reservoir the cover is moved 5 inwardly so that the lugs 13 engage both of the grooves 8^a and 8^b and the flange 10 is entirely within the reservoir. It will also be obvious that when this cover is in position the lubricant will be prevented from running 10 back into the reservoir and leaking out of the reservoir when the revolving of the wheel has caused the reservoir to assume an inverted position.

In the preferred construction it may be 15 mentioned that the bottom of the reservoir is inclined toward the tube 7 as indicated at 16 so as to permit the lubricant within the reservoir to drain freely toward the outlet.

From the foregoing description it will be 20 readily apparent that the improved lubricating device can be readily applied to the hub of an ordinary wheel and provides both a sand band for excluding foreign matter from the spindle and also enables the lubricant to 25 be applied to the spindle without the necessity of removing the wheel.

It may also be mentioned that the feed tube 7 is preferably formed separate from the reservoir and is provided at its upper end 30 with a flange 7^a received within a corresponding depression in the bottom of the reservoir. This manner of constructing the device enables the tube to be readily replaced should it be damaged by any accident, and also facilitates 35 cleaning thereof should it become clogged through the use of impure oil.

Having thus described the invention, what is claimed as new is:

1. An axle lubricator comprising a band 40 adapted to be applied to the hub of a wheel, an oil cup carried by the band and projecting beyond an edge of the same, and a feed tube leading from the projecting portion of the cup.

2. An axle lubricator comprising a split 45 band adapted to be applied to the hub of a wheel, an oil cup carried by the split band and projecting beyond an edge of the same, and a feed tube leading from the projecting portion of the cup. 50

3. In a lubricator, the combination of a reservoir formed with an annular groove, a cover provided with a flange adapted to be received within the reservoir, a spring carried by the flange, a lug projecting from the spring 55 and extending through the flange for coöperation with the groove to hold the cover in position, and a feed tube leading from the reservoir.

4. In a lubricator, the combination of a 60 reservoir formed with a pair of annular grooves, a cover provided with a flange adapted to be received within the reservoir, a spring carried by the flange, lugs projecting from the spring and extending through the 65 flange for coöperation with the grooves to hold the cover in an adjusted position, and a feed tube leading from the reservoir.

5. In a lubricator, the combination of a reservoir having a pair of annular grooves 70 formed in the interior walls thereof, a cover therefor, the said cover being formed with an annular flange adapted to be received within the reservoir, a spring strip applied to the flange and provided with a pair of locking lugs adapted to coöperate with the annular grooves to lock the cover in position with the flange either entirely or partially received 75 within the reservoir, and means for feeding lubricant from the reservoir. 80

In testimony whereof we affix our signatures in presence of two witnesses.
